UNITED STATES PATENT OFFICE.

ANDREW SMITH, OF CHICAGO, ILLINOIS.

PROPELLED DEVICE OR SHOOTER FOR TOYS.

1,308,201.

Specification of Letters Patent.

Patented July 1, 1919.

Application filed September 18, 1917. Serial No. 191,981.

To all whom it may concern:

Be it known that I, ANDREW SMITH, a citizen of the United States, residing in Chicago, county of Cook, and State of Illinois, have invented a certain new, useful, and Improved Propelling Device or Shooter for Toys, of which the following is a specification.

My invention relates to an improved disk 10 propelling device or shooter for use in games.

The object of my invention is to provide a device by means of which disks, such as checkers and similar playing devices, can be 15 readily and easily propelled as is necessary in the games of billiards, pool and ten-pins.

A further object of my invention is to provide a device of the character described which shall consist of but few parts which 20 shall be self-cocking, and which shall be so simple in its construction and operation that a child can readily use it.

My invention consists in a relatively fixed base member and a relatively movable member 25 pivotally mounted on the base member and having an arm terminating adjacent to the lower end of the base member adapted to be forced outwardly to propel a disk or the like positioned on the table upon which the 30 device stands, said arm being normally in a retracted position.

My invention also consists in a propelling lever pivotally mounted on a relatively fixed base, the lever having a substantially horizontal 35 arm at its upper end adapted to be struck by the hand, and a relatively vertical depending arm terminating adjacent to the lower end of the base and adapted to be forced outwardly from the base when the 40 horizontal arm is forced down, the lower end of the vertical arm being adapted for contact with a disk or the like for propelling or shooting same, means for holding the lever with its lower end retracted, and stops 45 for limiting the movement of the lever.

My invention also consists in the several features of construction and in the combinations of parts by which I am enabled to attain the above mentioned and other objects, 50 and all as hereinafter described and particularly pointed out in the appended claims.

My invention will be more readily understood by reference to the accompanying drawings forming a part of the specification, and in which:—

Figure 1 is a vertical central section of a

propelling device embodying my invention in one form and taken on the line 1—1 of Fig 2;

Fig. 2 is a vertical central section of the 60 device on the line 2—2 of Fig. 1; and

Fig. 3 is a horizontal section of the device on the line 3—3 of Fig. 1.

In games in which disks or similar pieces are shot or propelled across a game board it 65 has been customary to propel the disks by snapping them with the fingers. This requires a considerable degree of skill not only to properly direct the disk, but to propel it with sufficient force to properly play the 70 game. Furthermore as I have invented a game board particularly adapted for such games as billiards, pool, croquet and roque, all of which at times require the disk to be 75 propelled with considerable force in order to make the game interesting, I have found a necessity of having a simple device by means of which the disk can be easily propelled with any reasonable degree of force and fairly well directed in such action. 80

My propelling device consists of a pillar-like base member A having a flat bottom B upon which the base can stand steady in upright position on the game board C.

Preferably the base is rectangular in horizontal section as shown.

Upon the base I pivotally mount a swinging bell-crank lever D having one short arm E, and one long arm F. I preferably mount the lever D on the base to swing in a vertical plane by means of a horizontal pivot G placed adjacent to the forward edge of the upper end of the base. The short arm E is substantially horizontal and is adapted to be struck or forced down with the hand of 95 the player to operate the device while the longer arm is substantially vertical, its lower end H terminating adjacent to the lower end of the base A and adapted for contact with a disk, or the like, J for propelling 100 the same.

While the lever D might be mounted upon the base in many different ways to allow it the movement necessary to accomplish the result desired, I prefer to mount the lever 105 centrally upon the base providing a vertical groove K in the forward edge of the base to receive the inner portion of the arm F and a central horizontal groove L in the upper end of the base to receive the lower 110 portion of the short arm E.

For the purpose of holding the lever D

in retracted, position ready for operation, and with its lower end in contact with the lower part of the base, I overbalance the lever by extending the vertical arm F quite 5 a distance out in front of the base and the pivot G as shown at M. This addition is sufficient to more than counterbalance the rearwardly extending horizontal arm E. I so proportion the arm E that when the lever

10 is in retracted position, as shown in full line, Fig. 1, the lower face of edge N of the arm E is raised above the bottom O of the groove L, thus permitting the arm to descend a limited distance when it is forced 15 downwardly. I form the arm E so that its upper edge P projects at all times above the upper end of the base so that it is best adapted to be struck with the palm of the hand to force it down. I provide the lower 20 end H of the arm D with a rearwardly extending projection Q, its rear end adapted to contact with the bottom wall R of the groove K to limit the rearward or retracting movement of the lever.

25 For contact with the disks which are to be propelled, I preferably provide an upwardly inclined edge S on the forward part of the lower end H of the arm F, and I so arrange the lever that the point of contact

30 of the lever with the upper edge of the disk J, when the same is placed in position to be propelled, lies substantially below the pivot G. The inclination of the disk contacting edge or portion S permits the use of the de-

35 vice with substantially equal precision upon the disks or movable "men" of various thicknesses, thus adding to the range of usefulness of the device, and I have found that the inclined striking edge S propels the disks

40 with the least tendency to turn the disks over. In other words, the inclined striking or propelling edge S tends to cause the disks to slide across the board with their lower faces in contact with the surface of the 45 board upon which they are moving. I have found that an inclination of the propelling edge S of about 45 degrees serves to best propel the disks or movable "men".

Under usual conditions the counterweight 50 M is sufficient to hold the lever in a retracted or cocked condition, but I sometimes provide a light compression spring T mounted in a suitable vertical socket U and adapted to contact with the lower edge N of the arm 55 E and normally holding the lever retracted in an obvious manner.

In using my device the rectangular shape 60 of the base is of use in setting the device to properly direct the disk to be shot toward the object or place which it is desired to hit, and it will be apparent that when a disk or other similar game device is placed in contact with the lower end of the arm F, and the arm E is sharply struck with the hand, 65 the disk will be shot or forced away from

the device in accordance with the force with which the arm E is struck.

It will be apparent that to one skilled in the art many modifications of my invention will readily suggest themselves, and I therefore do not limit my invention to the specific forms and arrangements herein shown and described.

I claim:

1. A device of the character specified comprising a relatively fixed base member, a relatively movable member pivotally mounted on the base member adjacent to its upper end, a depending arm on said movable member terminating at its free end adjacent to the lower end of the base and adapted for contact with a disk, or the like, for propelling same away from the base, and means normally holding said arm in retracted position, a second arm rigid with said movable member adapted to be struck by the hand to cause said depending arm to propel a disk or the like.

2. A game shooter comprising a base having a flat bottom upon which the base stands in upright position, a bell-crank lever pivoted to the base, the free end of one arm thereof adapted for contact with a disk or the like positioned on the table or support upon which the shooter is placed, the other arm of the lever being adapted to be moved by the hand to cause the first mentioned arm to propel a disk, and means for normally retaining said lever in retracted position.

3. A game shooter comprising a pillar-like base member adapted to be stood on end for use, a bell-crank lever having two arms extending at substantially right angles to each other pivoted to said base, one arm depending and the other extending substantially horizontally, the depending arm terminating adjacent to the bottom of the base and adapted for contact with a disk or the like positioned upon the support upon which the shooter stands, the horizontal arm extending over the top of the base and adapted to be struck by the hand to force the lower end of the depending arm outwardly, and means for normally retaining the lower arm retracted and the horizontal arm raised.

4. A self-cocking shooter or propeller for games, comprising a pillar-like base member having a flat bottom upon which it can be stood for use, a bell-crank lever pivoted to the forward edge of the base and movable in a vertical plane, a depending arm on said lever terminating near the bottom of the base and adapted to contact with a disk or the like for propelling the same, a horizontal arm rigid with the depending arm and adapted to be struck to operate the device, said depending arm being weighted in such a manner that the horizontal arm is more than counterbalanced whereby the

lower end of the depending arm is normally held in a retracted position.

5. In a game shooter or propeller, a pillar-like base member adapted to be stood in upright position on a game board, a swinging lever on the pillar movable in a vertical plane and having a depending arm terminating adjacent to the bottom of the pillar, the forward edge of the lower end of said depending arm being adapted for contact with a disk or the like to propel the same, said disk contacting surface being inclined upwardly at an angle of substantially 45 degrees.
- 10 6. In a game shooter or propeller, a pillar-like base member adapted to be stood in upright position on a game board for use, a bell-crank lever pivotally mounted on said base by a pivot arranged at the upper end 20 of the base and substantially above the forward edge of the lower end thereof, said lever having a depending arm terminating at its lower end adjacent to the lower end of the base and provided with an inclined 25 disk-contacting edge arranged substantially below the pivot when the lever is in retracted position, said lever having a horizontal arm extending back over the top of the base and adapted to be struck to propel a disk, and 30 means for holding the lever normally in retracted position.
7. In a game shooter or propeller, a pillar-like base adapted to be stood on end upon a game board for use, a central vertical groove 35 in the forward edge of the base and a central
- horizontal groove in the upper end of the base, a bell-crank lever having arms lying within said grooves and pivoted to the upper end of the base to swing in a vertical plane, the arm in the vertical groove terminating 40 above the lower end of the base and adapted for contact with a disk or the like resting upon the support upon which the shooter is placed, the arm within the horizontal groove adapted to be struck by the hand to operate 45 the device, means holding the lower end of the vertical arm in retracted position in contact with the base.
8. In a game shooter or propeller, a rectangular pillar-like base adapted to be stood on end upon a game board for use, a bell-crank lever pivoted adjacent to its upper end for swinging in a vertical plane parallel with the side faces of the base, said lever having a depending arm terminating adjacent to 50 the lower end of the base and adapted to contact with a disk or the like placed upon the game board upon which the shooter is placed, an upper horizontal arm on the lever adapted to be struck to operate the device, 55 means for limiting the swinging movement of the lever and means for normally holding the lever in a retracted position.

In witness whereof I have hereunto set my hand this 15th day of September, 1917, 60
in the presence of one subscribing witness.

ANDREW SMITH.
